[57] CLAIM

The ornamental design for a meter register enclosure, as
shown and described.

DESCRIPTION

FIG. 1 is a perspective view of meter register enclosure
showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a top plan view with the lid of the enclosure
in an open position; and,

FIG. 9 is a left side elevational view of the enclosure
with a top lid in the open position.

The broken line showing of a water meter main housing
in FIG. 1 is for illustrative purposes only and forms no
part of the claimed design.
